MULTIPLE INPUT SWITCHING UNIT FOR A COMMUNICATION SYSTEM

Calvin L. Fox, New York, N.Y., assignor to Scanfax
Systems Corporation, New York, N.Y., a corporation
of New York

Filed Nov. 19, 1969, Ser. No. 20,182

Term of patent 14 years

Int. Cl. D13—03

U.S. Cl. D26—13

FIG. 2

FIG. 3

FIG. 4

FIG. 1 is a front perspective view of the design for a multiple input switching unit for a communication system; FIG. 2 is a back elevational view thereof; FIG. 3 is a bottom view thereof; and FIG. 4 is a right-side elevational view thereof.

I claim:

The ornamental design for a multiple input switching unit for a communication system, as shown.
